UNITED STATES PATENT OFFICE.

WILLIAM SCHWENN, OF NEW YORK, N. Y.

LUGGAGE CARRIER FOR AUTOMOBILES.

Application filed November 20, 1920. Serial No. 425,319.

To all whom it may concern:

Be it known that I, WILLIAM SCHWENN, a citizen of the United States, and a resident of the city of New York, county of Kings, 5 and State of New York, have invented a new and useful Improvement in Luggage Carriers for Automobiles, of which the following is a specification.

The object of my invention is to provide 10 a detachable and collapsible luggage carrier which may be applied to the running board of an automobile when desired, and removed readily and collapsed into a small space when not in use. This object is accomplished by my invention, one embodiment of 15 which is hereinafter more particularly set forth.

In the accompanying drawings, forming a part hereof,

20 Figure 1 is a side elevation showing my improved luggage carrier in use on an automobile.

Figures 2 and 3 are sectional views taken on the lines 2—2 and 3—3 respectively of 25 Figure 1, looking in the direction of the arrows.

Figure 4 is an enlarged detailed view showing a portion of the structure of the carrier.

30 Figure 5 is a sectional view taken on the line 5—5 of Figure 4, looking in the direction of the arrows.

Figures 6, 7, 8 and 9 show the luggage carrier in its collapsed form, Figure 6 showing 35 one side, Figure 7 the other side, Figure 8 an end, and Figure 9 a top plan view.

Throughout the various views of the drawings, similar reference characters designate similar parts.

40 My improved luggage carrier 1 may be applied to the running board 2 of any ordinary automobile, and it is held in place by means of three clamps 3, 4, and 5 respectively. Each of these clamps is composed of a screw 6 with a laterally extending handle and the screw passes through a bracket which is provided with a corresponding thread and at its top each screw is provided with a suitable washer 7 by means of which it is connected to the running board 2 of an automobile. Each set screw 6 forms a part of a clamp, the other part being one of the brackets 8, 45 10 and 9 which form parts of the clamps 3, 4 and 5 above mentioned, the center clamp 55 being the clamp 4. This center bracket is

pivotedly connected with the lazy tongs 11 which will be described below, and is placed at the lower middle portion of the same.

The end brackets 8 and 9 are preferably made, as shown in Figures 2 and 3, with a top bar 12, a vertical end 13 and a stud bar 14 through which the screw 6 passes which runs under the bar 12 and is parallel thereto, but extends only partially under, as shown. The top of each bar 12 at its inner end is riveted to a bent strap 15 which is provided with a horizontally disposed portion 16 (which is riveted to its bar 12) and the ends of this strap 15 extend upwardly and form two arms, one 17 going diagonally and the other 18, vertically, and finally it is bent near its top so as to be brought adjacent to the end of the arm 17 and the two ends are connected by a pivot 19 which is in the form of a rivet which also passes through an end 75 bar 20 which supports one end of the lazy tongs 11.

These bars 20 are identical except that the one shown in Figure 3 is horizontally disposed at the upper and lower ends 23 and 24 in shorter lengths than are the corresponding ends 21 and 22 shown in Figure 2. Both ends 22 and 24 are pivotally connected to their respective bars 12 by means of pivots 25 which are in axial alinement with their respective pivots 19. The purpose of making the webs 21 and 22 and one bar 20 of a different length of the corresponding webs 23 and 24 of the other bar 20 is to enable the bars 12 to lie parallel with each other as 85 shown in Figure 9 when the luggage carrier is collapsed.

The lazy tongs 11 is pivotally attached at its lower ends to the bar 20 by means of fixed pivots 26 and at its upper end by means of 95 movable pivots 27, each of which moves in a slot 28 which runs as shown in Figures 4 and 5. This slot 28 is made with a width which is narrower than the head of the rivet 27 and wider than the shank where it is connected to the lazy tongs 11 so that the most reduced portion may pass through a perforation in the corresponding upper end of the lazy tongs 11 where it is fixed.

The U bracket 10 is secured to a plate 29 105 which has a pivot 30 which connects it to the lower center portion of the lazy tongs 11. This pivot 30 forms one of the pivots of the lazy tongs.

In view of the foregoing the operation and 110

use of my improved luggage carrier will be readily understood.

- Assuming the device to be erected it is used as shown in Figure 1 where the luggage 31 is placed on the running board 2 of an automobile and between the body 32 of the automobile and the lazy tongs 11 and end straps 15. These end straps are separated any desired amount, according to the 10 luggage which is interposed between them, and are preferably so placed that they will rest snug against the ends of the luggage. When so placed, the screws 6 are tightened and the carrier is in the position shown.
- Assuming that it is no longer desired to keep the luggage carrier in use it may be removed by loosening the screws 6 and removing the carrier 1 and collapsing the lazy tongs 11, after which the U clamp 10 is 20 thrown into a horizontal position snug against the lazy tongs 11 and adjacent to the short shank 24. The end pivotally connected to this short shank is then thrown down against the lazy tongs 11 and therefore 25 after the other end is thrown down on it and then the carrier is collapsed without bending or straining and into a minimum space. By reversing these operations it may be erected and applied. It is obvious that 30 the curvature of the upper ends of the parts 18 enables these bars to get under the swell of the body 32 of an automobile so that these ends may be used on any style or make of car, and they are, therefore, universal in 35 their application.

While I have shown and described one embodiment of my invention, it is obvious that it is not restricted thereto, but that it is broad enough to cover all structures that 40 come within the scope of the annexed claims.

Having thus described my invention, what I claim is:

1. A luggage carrier provided with a lazy tongs and ends with parts pivotally connected together and to said lazy tongs with fixed and movable pivots, said pivots in said ends being placed at unequal distances from said lazy tongs so that the parts of said ends may be folded parallel with said lazy tongs and in different planes so that the carrier may be collapsed into a minimum space without straining.

2. A luggage carrier provided with a lazy tongs, ends with parts pivotally connected together and to said lazy tongs with fixed and movable pivots, said pivots in said ends

being placed at unequal distances from said lazy tongs so that the parts of said ends may be folded parallel with said lazy tongs and in different planes so that the carrier 60 may be collapsed into a minimum space without straining and a clamp pivotally connected to the lower edge of the lazy tongs intermediate of its ends.

3. A luggage carrier provided with a lazy 65 tongs and ends with parts pivotally connected together and to said lazy tongs with fixed and movable pivots, said pivots in said ends being placed at unequal distances from said lazy tongs so that the parts of said ends 70 may be folded parallel with said lazy tongs and in different planes so that the carrier may be collapsed into a minimum space without straining, each of said ends being provided with a grooved bar which may be 75 placed close to the body of an automobile without interfering with the swell of the same above the running board.

4. A luggage carrier provided with lazy 80 tongs and ends with parts pivotally connected together and pivoted to said lazy tongs, said pivots in said ends being placed at unequal distances from said lazy tongs so that the parts of said ends may be folded 85 parallel with said lazy tongs and in different planes so that the carrier may be collapsed into a minimum space without straining.

5. A luggage carrier provided with lazy 90 tongs and ends with parts pivotally connected together and pivoted to said lazy 95 tongs, said pivots in said ends being placed at unequal distances from said lazy tongs and so that the parts of said ends may be folded parallel with said lazy tongs and in different planes so that the carrier may 100 be collapsed into a minimum space without straining and a clamp pivotally connected to the lower edge of the lazy tongs intermediate of its ends.

6. A luggage carrier provided with lazy 100 tongs and ends with parts pivotally connected together and operatively connected with said lazy tongs, said pivots in said ends being placed at unequal distances from said lazy tongs so that the parts of said ends 105 may be folded parallel with said lazy tongs and in different planes so that the carrier may be collapsed into a minimum space without straining.

In testimony whereof, I have set my hand 110 this 15th day of November, 1920.

WILLIAM SCHWENN.
